COIN ACTUATED LOCKING DEVICE FOR TELEPHONES

Original Filed Oct. 22, 1925

Inventor:

Frank L. Lockwood,

by John Middleton Donaldson Hall

Atty's.

UNITED STATES PATENT OFFICE.

FRANK L. LOCKWOOD, OF WASHINGTON, DISTRICT OF COLUMBIA.

COIN-ACTUATED LOCKING DEVICE FOR TELEPHONES.

Application filed October 22, 1925. Serial No. 64,215.

The present invention relates to improvements in coin actuated locking attachments for telephones of the desk type, and aims to provide a construction which will be simple and efficient, and not likely to get out of order, which may be very economically manufactured, and one that can be easily applied to the telephone set by the ordinary user.

10 With these, and other objects in view, which will hereinafter appear, the invention comprises the novel features of construction and arrangement and combination of parts hereinafter described, and particularly defined by the appended claims.

What is at present considered the preferred embodiment of the invention is illustrated in the accompanying drawings, in which:—

20 Figure 1 is an elevation of the ordinary telephone set or stand, shown largely in a conventional manner, with the locking attachment in place thereon, and

25 Fig. 2 is a detail view, partly in section, showing the attachment as viewed from the right of Fig. 1.

Fig. 3 is a detail view also partly in section, as viewed from the rear of Fig. 1.

30 Fig. 4 is a transverse vertical section taken just in front of or to the left of Fig. 6, of the member 7.

Fig. 5 is a vertical transverse section on the line between parts 6 and 7.

35 Fig. 6 is a section on line 6—6 of Fig. 4.

Fig. 7 is a view similar to Fig. 6, but showing the parts in switch arm releasing position.

40 Fig. 8 is a section on line 8—8 of Fig. 4, and showing the position of the parts with the key inserted in inverted position.

Fig. 9 is a similar section with the key inserted in reversed position, or right side up.

45 Fig. 10 is a section on line 10—10 of Fig. 4, and

Fig. 11 is a similar section taken just above the dog or member 10.

50 Referring to the several figures of this drawing by reference characters, the numeral 1 designates the telephone stand having the usual transmitter 1^a, and receiver supporting switch 1^b, which is automatically raised by the removal of the receiver 1^c from the switch arm. 2 designates a coin receptacle, 55 which is provided with a door or removable

closure 2^a normally held closed by a suitable lock adapted to be unlocked by a key to permit it to be opened for removal of the coins by the holder of the key.

This receptacle is provided at one side 60 with a convex wall portion or recess 2^b designed to fit against the upright portion or pedestal of the stand just below the switch arm, being clamped in position by a clamping member 3 which may be secured to the receptacle wall in any convenient manner, as by means of bolts 4, the securing nuts of which may be located within the receptacle to prevent their removal except when the door is open.

70 The receptacle 2 is provided at one corner with an upstanding coin chute 5 which also carries the coin actuated mechanism herein-after described, and which communicates with the coin receptacle by a coin slot 2^c, 75 the bottom of the chute being inclined as shown, to deflect the coin into the receptacle from the lower end of the chute.

Said bottom is made as a separate piece to permit the entry of the coin actuated parts, 80 whereafter it may be riveted or brazed in position.

85 The upper end is provided with a recess or slot in which is slidably located a switch arm retaining member 6, the upper end of which is laterally recessed, as indicated at 6^a to engage the switch arm, as shown, it being understood that when the member 6 is free to move vertically, this switch arm will rise on removal of the receiver therefrom.

90 Lying alongside of and cooperating with the member 6 is a member 7 having an elongated slot 7^a therein, within which is pivotally mounted a coin actuated lever 8 having at its upper end a lug or projection 8^a designed to engage a shoulder on the member 6, which shoulder may be conveniently and economically formed by the bottom edge of an opening 6^b.

95 The lever 8 is acted on by a light spring 9, preferably coiled about the pivot pin 8^b of the lever and having one end or arm bearing against the member 7 and the other against the lever. The lower end 8^c of the lever is deflected outwardly towards the wall of the coin chute and is so positioned and proportioned that when a nickel has been inserted in the coin receiving slot 5^a and drops downwardly under the action of 100 105 110

gravity, it will press the inclined or deflected lower end of the lever laterally and disengage the lug 8^a from the switch lever holding member, thereby unlocking or free-
5 ing said switch arm to permit the telephone to be operated as before explained, and as shown in Fig. 6. The said lower end of the lever may be so positioned relative to the adjacent wall of the coin slot that a
10 thinner coin, such as a penny or dime will not move the lever into unlocking position.

At the lower end of the slot or recess 7^a is a pivoted dog 10 one edge of which normally projects into the path of the coin, preventing it from passing into the coin receptacle after the releasing lever has been actuated and before the switch lever has been raised, in which position said dog 10 is held by the lower end of the member 6
20 overlying and abutting against the upper face of the opposite end of said dog. When the receiver is removed from the hook and the switch arm raises the member 6, the dog 10 is released and tipped by the weight of
25 the coin which is permitted to drop into the coin receptacle.

In order that the owner of the telephone may use it without resorting to a coin for unlocking purposes, I provide the coin chute 30 5 with a key slot or opening 5^b, preferably designed to admit the same key which unlocks the door of the coin receptacle. The member 6 is provided with a transverse groove 6^d in its face in alignment with the locking dog or projection 8^a, which latter projection is beveled or inclined at one side (Figs. 6 and 10), so that insertion of the key and pushing its end against the dog will cause the latter to release the member 6, the
35 key slot 5^b being of sufficient length that when the member 6 is released the key can move up with it.

It is desirable that means shall be provided whereby the owner may, on leaving his office, lock the phone against coin controlled use.

To this end I provide the slide 6 with an L-shaped recess 6^e, Fig. 5, in which is pivoted a dog 11 having a laterally extending locking wing or projection 11^a designed to cooperate with a corresponding recess 7^b, in member 7 (see Figs. 8 and 9).

The lower portion of the dog 11 (right hand edge, Fig. 5) is provided with two reversely beveled portions shown respectively in full and dotted lines in Fig. 5, designed to cooperate with the end corner projection with which flat keys are customarily provided.

60 When the key is inserted right side up or with its corner extension uppermost, and pushed to the limit, said corner projection acting on the upper incline will swing the dog end or portion 11^a into engagement with the recess 7^b in element 7, as shown in Fig. 9

in which position it will be frictionally held upon removal of the key by a spring pressed friction plunger 12 in the top edge of the dog coacting with the upper wall of the recess 6^e. Insertion of the key in its inverted position will cause the extension to coact with the lower bevel portion of the dog which will swing the dog back to the position shown in Fig. 8, thus restoring the parts to normal position.

70 To prevent the liability of the attachment being twisted on the phone standard 1, in case the clamp is not sufficiently tight, by which twisting action the switch arm might be freed from the slot 6^a, I provide the casing 5 with an integral extension 5^x which overlies and closes the open side of the slot.

75 From the foregoing, it will be seen that a very simple form of apparatus is provided and one which may be very economically manufactured, as all the main parts may be stamped up or died out of sheet metal of the requisite thickness and easily assembled and very little machine work is
80 necessary.

85 Having thus described my invention, what I claim is:

1. A telephone attachment of the class 90 described, comprising a coin receptacle with means for securing it to a telephone stand, said receptacle having a substantially vertically disposed coin chute casing communicating with said receptacle, a vertically slide-
100 able switch arm engaging member slidably guided by said coin chute casing and having a locking shoulder, a recessed member lying alongside said switch arm engaging member and spaced from the adjacent wall of the coin chute casing to provide a coin passage, and a locking lever pivoted in said recess and having one end provided with a dog for engaging said shoulder, and its other end lying normally in inclined position in
105 said coin passage.

110 2. A telephone attachment of the class described comprising a coin receiving receptacle with means for securing it to a telephone stand, said receptacle having an up-
115 standing coin chute communicating with said receptacle, a switch arm engaging member slidably guided by said chute and having a locked shoulder, a recessed member lying alongside said locking member, a locking lever pivoted in said recess and having a dog engaging said shoulder, and an inclined end lying in the path of the coin, and a coin retaining member pivotally mounted beneath the lower end of said lever and having one end projecting into the path of the coin and its other end underlying the lower end of said switch arm engaging member.

120 3. A telephone attachment of the class described, comprising a coin receptacle with 125 means for securing it to a telephone stand,

- said receptacle having a substantially vertically disposed coin chute casing communicating with said receptacle, a vertically slideable switch arm engaging member slidably guided by said coin chute casing and having a locking shoulder, a recessed member lying alongside said switch arm engaging member and spaced from the adjacent wall of the coin chute casing to provide a coin passage, a locking lever pivoted in said recess and having one end provided with a dog for engaging said shoulder, and its other end lying normally in inclined position in said coin passage, and key actuated means carried by said recessed member for moving said locking lever to unlocking position.
4. A telephone attachment of the class described, comprising a coin receptacle with means for securing it to a telephone stand, said receptacle having a substantially vertically disposed coin chute casing communicating with said receptacle, a vertically slideable switch arm engaging member slidably guided by said coin chute casing and having a locking shoulder, a recessed member lying alongside said switch arm engaging member and spaced from the adjacent wall of the coin chute casing to provide a coin passage, a locking lever pivoted in said recess and having one end provided with a dog for engaging said shoulder, and its other end lying normally in inclined position in said coin passage, and key actuated means carried by said recessed member for locking the switch arm engaging member thereto.
5. A telephone attachment of the class described comprising a coin receiving receptacle with means for securing it to a telephone stand, said receptacle having an upstanding coin chute communicating with said receptacle, a switch arm engaging member slidably guided by said chute and having a locking shoulder, a recessed member lying alongside said locking member, a locking lever pivoted in said recess and having a dog engaging said shoulder, an inclined end lying in the path of the coin, said dog having an inclined side face, and said chute and switch arm engaging member having aligning key passages for insertion of a push key to engage the inclined face of the dog.
6. A telephone attachment of the class described, comprising a casing with means for securing it to a telephone stand, a vertically slideable member guided in said casing and having a laterally opening switch arm engaging recess, and a coin actuated lever pivoted within the casing and having a dog engaging said member to normally restrain it from upward movement, said casing having an extension lying alongside the switch arm and closing the open side of said recess.
7. A telephone attachment of the class described comprising a coin receiving receptacle with means for securing it to a telephone stand, said receptacle having an upstanding coin chute communicating with said receptacle, a switch arm engaging member slidably guided by said chute and having a locking shoulder, a recessed member lying alongside said locking member, a locking lever pivoted in said recess and having a dog engaging said shoulder, an inclined end lying in the path of the coin, and means for locking the parts against coin actuation comprising a dog pivoted in a recess in one of said members and adapted to engage a recess in the other member, said dog having a part provided with reversely inclined cam faces at different elevations, there being a key slot leading to said cam faces whereby a key may be inserted to actuate said dog.
8. A telephone attachment of the class described, comprising a coin receiving receptacle with means for securing it to a telephone stand, said receptacle having an upstanding coin chute communicating with said receptacle, a switch arm engaging member slidably guided by said chute and having a locking shoulder, a recessed member lying alongside said locking member, a locking lever pivoted in said recess and having a dog engaging said shoulder, an inclined end lying in the path of the coin, and means for locking the parts against coin actuation comprising a dog pivoted in a recess in one of said members and adapted to engage a recess in the other member, said dog having a part provided with reversely inclined cam faces at different elevations, there being a key slot leading to said cam faces whereby a key may be inserted to actuate said dog, and friction means for holding said dog in either its locked or unlocked position.

In testimony whereof, I affix my signature.
FRANK L. LOCKWOOD.
